Richard Seier
ATTORNEY.

UNITED STATES PATENT OFFICE.

OSCAR A. BOEHM, OF NEW YORK, N. Y.

SPARK PLUG.

Application filed November 24, 1920. Serial No. 426,242.

To all whom it may concern:

Be it known that I, OSCAR A. BOEHM, a citizen of the United States of America, residing at New York, county of New York, 5 and State of New York, have invented certain new and useful Improvements in Spark Plugs, of which the following is a specification.

My invention relates to spark plugs such 10 as are used for ignition purposes, particularly in connection with internal combustion engines.

The object of my invention is to provide 15 a spark plug which (without the use of auxiliary spark gaps) will exhibit a luminous effect when in normal operation, such effect being absent when the plug fails to operate for any reason. Another object of the invention is to provide a very simple, strong, 20 and inexpensive construction which will be practically leakproof and free from short-circuit troubles.

Two typical embodiments of my invention are illustrated by the accompanying drawings, in which Fig. 1 is an outside view of a 25 spark plug constructed according to my invention; Fig. 2 is a longitudinal section thereof on line 2—2 of Fig. 1; Fig. 3 is a cross section on line 3—3 of Figs. 1 and 2; Fig. 4 is an end view looking in the direction of the arrow 4 in Fig. 1; Fig. 5 is a 30 longitudinal section of another form of my invention on line 5—5 of Fig. 6, the latter being an end view thereof looking in the 35 direction of the arrow 6 in Fig. 5.

The improved spark plug comprises a tubular metal body having the usual screw thread 10 for securing the spark plug to a support, generally the cylinder head of the 40 engine. Said body also has the usual angular portion 11 for the application of a wrench, and a bent wire or electrode 12 near the free end of the threaded portion 10. The inner surface of said tubular body is tapered 45 outwardly, its diameter being greatest at the threaded portion 10. Preferably said tapering inner surface is made with longitudinal ribs 13.

Within the tubular body is arranged the 50 tubular carrier 14 for the inner electrode 15, the latter being a rod or wire disposed axially and preferably projecting beyond the inner ends of the body and of the carrier 14,

the outer electrode 12 being in this case located to one side of the inner or central electrode. This carrier 14 is made of glass or other suitable resistant material which is a non-conductor of electricity and pervious to light (transparent or translucent). The outer surface of the carrier 14 is tapered at the same angle as the inner surface of the metal body, or approximately so, and a portion of said carrier has an external diameter greater than the smallest internal diameter of the metal body (at the outer end), so that the carrier 14 may be wedged tightly within the metal body, as shown. A layer 16 of suitable cement is placed between the adjacent surfaces of the body and of the carrier. The ribs 13 form grooves which cause the cement to dry more quickly, in the manufacture of the plug. The bore of carrier 14 of larger diameter than the electrode 15, leaving a free space or chamber 17 between the said electrode and the wall of the carrier. 75 The inner end of the carrier 14 is open, so that the chamber 17 of said carrier is in communication with the space (generally the combustion chamber of the engine cylinder) in which the spark is produced between the electrodes 12, 15. The outer end of the tubular carrier 14 is closed in any suitable manner, as by means of a metal cap 18 fitted to said end and to the threaded outer end 15' of the electrode 15, a filling 19 of 80 suitable cement being applied at this point to hold said electrode in place firmly. The threaded end 15' also receives the wire connection and clamping nut which have not been shown, as they may be of usual construction.

A spark plug of this construction will not crack, is practically leakproof, and will not short-circuit, and is inexpensive to manufacture. Every time a spark jumps between the electrodes 12, 15, the chamber 17 will become luminous, and since the carrier 14 is pervious to light, the luminous effect will be plainly visible while the engine is in operation. Absence of this effect will 95 indicate that no spark is being produced. It will be noted that my invention affords a ready means for testing or watching the operation of the spark plug continuously, without disconnecting the plug from the 100 circuit and without the use of auxiliary

spark gaps or like expedients which increase the consumption of current or have other drawbacks.

The carrier 14 of Figs. 1 to 4 is tapered 5 for the full length of the metal body and cemented to the entire inner surface of said body. In Figs. 5 and 6, the carrier 14' has a contracted inner portion 14'' which is spaced from the metal body to form an annular chamber 20 open at the inner end, this arrangement being preferred in many cases. In this second form of my invention the carrier 14' is cemented to the inner surface of the metal body only for a portion 10 of the length of said body. The ribs 13 in this case need not extend to that portion of the metal body which is adjacent to the contracted portion 14''. Another difference consists in the fact that in Figs. 15 5 and 6, the inner end of the carrier is even with the inner end of the metal body, where-

as in Figs. 1 to 4 the inner end of the carrier 14 projects beyond the inner end of the metal body.

Various modifications may be made without departing from the nature of my invention as set forth in the appended claim.

I claim:

A spark plug comprising a tubular body adapted for connection with a support and having an outwardly tapering inner surface provided with longitudinal ribs, a tubular carrier closed at its outer end and open at its inner end, said carrier being set within said body and having a tapered outer surface corresponding to the tapered inner surface of said body, and an electrode extending through said carrier and supported thereby. 30 35

In testimony whereof I have affixed my signature.

OSCAR A. BOEHM.
